US0D1090053S

(12) **United States Design Patent** (10) **Patent No.:** **US D1,090,053 S**
(45) **Date of Patent:** **** Aug. 26, 2025**

(54) **PERSONAL CARE DEVICE HANDLE**

(71) Applicant: **Church & Dwight Co., Inc.**, Princeton, NJ (US)

(72) Inventors: **Robert W. Fusi, II**, Flemington, NJ (US); **Jason B. Wilds**, Yardley, PA (US); **Sergio Gedanke**, Brooklyn, NY (US); **John Almstead**, Haddonfield, NJ (US); **Ryan Patrick Donovan**, Princeton, NJ (US); **Christopher B. King**, Philadelphia, PA (US); **Kelly Gail Duncan**, Bethlehem, PA (US); **Paul D. Carse**, Milford, NJ (US); **William H. Carr**, Phillipsburg, NJ (US); **Matthew L. Norris**, Easton, PA (US)

(73) Assignee: **Church & Dwight Co., Inc.**, Princeton, NJ (US)

(**) Term: **15 Years**

(21) Appl. No.: **29/862,233**

(22) Filed: **Dec. 7, 2022**

(51) LOC (15) Cl. **28-03**

(57) **CLAIM**

The ornamental design for a personal care device handle as shown and described.

DESCRIPTION

FIG. 1 is a front perspective view of a personal care device handle showing our design;

FIG. 2 is a rear perspective view thereof;

FIG. 3 is front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines shown in the drawings illustrate portions of the personal care device handle that form no part of the claimed design. The dash-dot-dash broken lines represent a boundary of the claim and form no part of the claimed invention.

1 Claim, 6 Drawing Sheets
